THREE-LEGGED DOMICAL SHELTER

John S. Sumner, 728 N. Sawtelle Ave.,
Tucson, Ariz. 85716

Filed June 12, 1973, Ser. No. 369,188

Term of patent 14 years

Int. Cl. D25—03

U.S. Cl. D13—1 D

FIG. 1 is a perspective view of a three-legged domical shelter with vertical walls;

FIG. 2 is a side view of the three-legged domical shelter shown in FIG. 1 looking through one of the three outside arches with a portion broken away for clarity;

FIG. 3 is a perspective view of the three-legged domical shelter shown in FIG. 1 looking upward from below its base toward the inner surface of the dome; and

FIG. 4 is a bottom view of the three-legged domical shelter shown in FIG. 1.

I claim:

The ornamental design for the three-legged domical shelter, as shown and described.
